UNITED STATES PATENT OFFICE.

JULIUS GREENSTEIN AND JENÖ LEDNITZKY, OF NEW YORK, N. Y.

DETACHABLE HEEL.

No. 852,178.

Specification of Letters Patent.

Patented April 30, 1907.

Application filed July 18, 1906. Serial No. 326,724.

To all whom it may concern:

Be it known that I, JULIUS GREENSTEIN, a citizen of the United States, and I, JENÖ LEDNITZKY, a citizen of the Kingdom of Hungary, and residents of the city of New York, in the county of New York and State of New York, have invented certain new and useful Improvements in Detachable Heels, of which the following is a specification.

10 The invention relates to improvements in detachable heels for boots and shoes, and particularly to means for fastening detachable heel sections to the heel of a boot or shoe.

15 The object of the same is to improve the construction of detachable heels; more especially the means for detachably interlocking a heel with a boot or shoe, and to provide a simple, inexpensive and efficient device of 20 great strength and durability, adapted to be readily applied to a shoe and capable of quickly being removed from a shoe, when desired, whereby one heel-section may be replaced by another in the event of wear or 25 other injury to the first one, and, in some instances, to permit different forms of heel-sections to be used on a single pair of boots or shoes.

The invention consists in the construction 30 and novel combination and arrangement of parts hereinafter fully described, illustrated in the accompanying drawings, and pointed out in the claims.

In the drawings, Figure 1 is a longitudinal 35 sectional view of a portion of a shoe, provided with a detachable heel constructed in accordance with this invention. Fig. 2 is a transverse sectional view of the same in line 2—2 of Fig. 1. Fig. 3 is a horizontal section 40 of the same in line 3—3 of Fig. 2. Fig. 4 is a detail of construction. Fig. 5 is a transverse sectional view of a modified form of the invention.

In the said drawings the reference numeral 45 1 designates a shoe of any preferred shape or style, having the usual sole 2. A plate 3 is secured to the latter by nails, screws or other fastening devices. The plate is preferably made of metal or hard rubber and conforms 50 to the shape of the heel. A plurality of bolts or pins 4, provided with notches 5, are attached to it in any suitable manner, the notches to be engaged by a spring 6 of ap-

proximately U shape attached to the lower plate 7 by brackets 8 and 9, which allow a 55 lateral movement of the spring, the purpose of which will be hereinafter described. The spring 6 is located in a U-shaped recess closed wall sides, except the straight front-end of the heel. oc

The plate 7 is secured to the upper portion of the detachable heel section 10 by nails, or other fastening devices. The plates 3 and 7 are precisely of the same dimensions, one having a plurality of holes of apertures 11, which are engaged by the bolts or pins of the other and provide thereby means for preventing the longitudinal and lateral movement of the detachable heel section, while the spring 6 securely holds the same against vertical movement. 70

Fig. 5 shows a modified form of the invention. A plurality of bolts or pins 12 is attached to the plate 3, comprising a screw-threaded part 13, by means of which the bolt is secured to the plate 3, furthermore a shank 14 and a point 15. The shank is engaged by the spring 6 and holds thereby the detachable heel section securely against vertical movement, while the points 15, engaging the holes or apertures 11, having in this present case conical shape, prevent the lateral and longitudinal movement of the heel. 80

Should it be desired to apply the detachable heel section to the boot or shoe, the pins of the heel are placed into the holes of the section, the U shaped spring engages the notches of the bolts and prevents thereby the removal of the detachable heel section from the permanent heel portion. To remove the detachable heel section, the spring 6 is pressed together from the open end of the recess by a suitable tool, whereby it disengages from the notches, and the bolts can then be easily removed from the holes, whereby the heel section is detached. 85

As new and useful is claimed and desired to be secured by Letters Patent of the United States:—

In a boot or shoe, the combination with a permanent sole, of a plate secured thereto, a plurality of bolts attached to said plate, a removable heel-section, a companion-plate secured to said removable heel-section and having a plurality of holes adapted to be en- 100
105

gaged by said bolts, and a U-shaped spring attached to said companion-plate and suitable to engage all of said bolts and adapted to become disengaged from said bolts by 5 being pressed together from the front-end of said detachable heel-section.

Signed at New York in the county of New

York and State of New York the fifth day of July, A. D. 1906.

JULIUS GREENSTEIN
JENÖ LEDNITZKY.
